UNITED STATES PATENT OFFICE.

CHARLES LINSTROM, OF VICKSBURG, MISSISSIPPI.

ECCENTRIC.

SPECIFICATION forming part of Letters Patent No. 565,169, dated August 4, 1896.

Application filed December 19, 1895. Serial No. 572,626. (No model.)

To all whom it may concern:

Be it known that I, CHARLES LINSTROM, a citizen of the United States, residing at Vicksburg, in the county of Warren, State of Mississippi, have invented certain new and useful Improvements in Eccentrics, of which the following is a full, clear, and exact specification.

This invention relates to eccentrics designed for the driving-shafts of locomotives, stationary and marine engines, and generally whenever an eccentric is used for converting motion.

The chief object of the invention is to provide a new and improved sectional eccentric which can be rigidly secured to a shaft without the use of a set-screw extending into the bore of the eccentric to bear or act against the shaft and without liability of the sections becoming separated or disconnected from operative position.

The invention also has for its object to provide a sectional eccentric which can be rigidly clamped radially upon a shaft without the use of a set-screw and without liability of the parts being forced from their correct operative position.

To accomplish these objects, the present invention consists in the features of construction and in the combination or arrangement of parts hereinafter described and claimed, reference being made to the accompanying drawings, in which—

Figure 1 is a sectional view of a shaft, showing the improved eccentric in side elevation and clamped to the shaft. Fig. 2 is a sectional elevation showing the complementary section of the eccentric separated from the main section, and Fig. 3 is a detail perspective view of the yoke-shaped clamp for rigidly securing the main section of the eccentric to the shaft.

In order to enable those skilled in the art to make and use my invention, I will now describe the same in detail, referring to the drawings, wherein—

The letter C indicates a shaft, which may be the driving shaft or axle of a locomotive, or a stationary or marine engine, or any other shaft which is to be provided with an eccentric for converting motion.

The eccentric proper is in the form of a

disk, composed of a main section A and a complementary section A'. The main section is constructed, as shown, with transverse perforations A⁴ and two substantially parallel passages A³, which extend transverse to the geometric axis of the shaft and open at one end into the perforations A⁴. The main section is also formed integral or otherwise constructed with two opposing jaws A⁵, which are adapted to lie at opposite sides of the shaft C, so that their abutting faces are opposite each other. The two passages A³ are designed to receive the arms D' of a U-shaped yoke D, having its circular portion adapted to partially encircle and fit against the shaft C. The arms D' of the yoke extend into the perforations A⁴ and are provided with screw-threaded extremities D³, for the purpose of receiving rotary screw-nuts D², in such manner that by tightening the nuts the yoke is bound upon the shaft, and the main section of the eccentric is thereby rigidly clamped in position.

The complementary section A' of the eccentric is substantially in the form of a segment, adapted to be inserted between the opposing jaws A⁵, so that the extremities of the segment bear against the faces of the jaws. The complementary section is properly curved to more or less accurately fit the shaft C, and this section is retained in operative connection with the main section A through the medium of transverse bolts B, which extend through bolt-holes formed partially in the jaws A⁵ and partially in the ends of the complementary section A'. The bolt-holes are preferably countersunk at their extremities, so that they may receive the heads and the nuts of the bolts, as will be obvious. The opposing jaws A⁵ serve as abutments for the ends of the complementary section, and the acting faces of the jaws are, as shown, arranged to extend in a direction transverse to the geometric axis of the shaft, so that in the rotary motion of the eccentric the jaws carry the complementary section in the circular path, and thereby relieve the transverse bolts B almost entirely of strain in the direction of motion of the eccentric.

It will be obvious that the improved eccentric can be applied to a shaft without slipping it upon the shaft from one end of the latter,

and that the eccentric can be set to the desired position on the shaft and then be rigidly clamped thereto without liability of being forced from its correct operative position.

5 The yoke-clamp D is preferably in the form of a flattened bar or strip of metal having cylindrical end portions which are provided with the screw-threads to engage the screw-threads of the rotary nuts; but I do not wish 10 to be understood as confining myself to this exact construction of the yoke-clamp; nor do I wish to be understood as confining myself to the exact arrangement shown of the transverse bolts for retaining the complementary 15 section in operative connection with the two jaws of the main section, as this may be accomplished by any devices suitable for the purpose.

The passages A³, through which the arms 20 of the yoke-clamp, extend, as shown, tangentially to the periphery of the shaft C, as by this means the yoke-clamp can be made to more effectively clamp the main section of the eccentric radially upon the shaft. The passages A³ are preferably arranged centrally 25 between the opposite sides of the body of the eccentric, but this arrangement may be more or less varied without altering the character of my invention.

30 The curved face of the complementary section A, which is designed to fit a peripheral portion of the shaft C, is constructed with a segmental groove A² to receive and accommodate the curved portion of the yoke-clamp 35 D, so that an accurate fitting of the parts is obtained, and the complementary section can be nicely set into position between the jaws of the main section.

The improved eccentric may be used for 40 any purpose for which an eccentric is ordinarily used, but it is chiefly designed for the driving-shafts of locomotives and for the shafts of stationary and marine engines.

Having thus described my invention, what 45 I claim is—

1. An eccentric, consisting of a disk having an eccentric bore and composed of a main section and a complementary section, the main section provided with opposing jaws 50 projecting past the major diameter of the shaft on which the eccentric is to be mounted and having their inner faces extending transversely of said shaft, a clamp constructed to engage said shaft and extending through a 55 part of the main section in a plane transversely to the axis of the shaft for clamping the main section thereupon, and means for retaining the complementary section between and against the said transverse inner faces of 60 the opposing jaws of the main section, substantially as described.

2. An eccentric, consisting of a disk having an eccentric bore and composed of a main section and a complementary section, the

main section having opposing jaws with their 65 inner faces extending transversely of the shaft on which the eccentric is to be mounted, and the complementary section being inserted between and having its ends abutting said inner faces of the opposing jaws, a clamp 70 for rigidly clamping the main section upon the shaft, and means independent of said clamp for retaining the complementary section in operative connection with the said opposing jaws, substantially as described. 75

3. An eccentric, consisting of a disk having an eccentric bore and composed of two sections, one a main section having opposing jaws and the other a complementary section 80 inserted between and having its ends abutting said opposing jaws, a yoke-clamp constructed to partially encircle a shaft and having its arms engaged with the main section, nuts mounted on the arms of the yoke-clamp, and means for retaining the complementary 85 section in operative position, substantially as described.

4. An eccentric, consisting of a disk having an eccentric bore and composed of a main section and a complementary section, the main section provided with opposing jaws 90 extending past the major diameter of the shaft on which the eccentric is to be mounted and having their inner faces arranged transversely of said shaft, and the complementary 95 section constructed with a curved or segmental groove and having its ends abutting said transverse inner faces of the opposing jaws, a yoke-clamp partially encircling the shaft, lying in the groove of the complementary 100 section and formed with two arms engaging the main section, nuts mounted on the arms of the yoke-clamp for causing it to rigidly 105 secure the main section to the shaft, and means independent of said yoke-clamp for retaining the complementary section between two jaws of the main section, substantially as described.

5. The combination in an eccentric having an eccentric bore, of main and complementary disk-sections in which said bore is formed, the complementary section having a groove running around a portion of the bore, and the main section having two passages extending transversely to the axis of the bore, 110 a yoke-clamp having a curved portion fitting in the groove of the complementary section, and two arms passing through passages in the main section, means for clamping the yoke-clamp and the main section upon a shaft, 115 and means for retaining the complementary section in rigid connection with the main section, substantially as described. 120
